(57) **CLAIM**

The ornamental design for handles for pivoted hand tools, as shown and described.

DESCRIPTION

FIG. 1 is a perspective view of a pivot hand tool with the handles;

FIG. 2 is a second perspective view thereof;

FIG. 3 is a front view thereof;

FIG. 4 is a rear view thereof;

FIG. 5 is a right end view thereof;

FIG. 6 is a left end view thereof;

FIG. 7 is a top plan view thereof; and,

FIG. 8 is a bottom plan view thereof.

The broken lines in the drawings illustrate the environment of the claimed design and form no part thereof.
